GRIP EXERCISER

Adrian D. Vick, Washington, D. C.

Application March 30, 1938, Serial No. 199,030

1 Claim. (Cl. 272—68)

This invention relates to grip exercisers for developing the muscles of the hand, and has for an object to provide a device of this character having a wire frame provided with lateral extensions, and having a sliding grip on the frame provided with extensions, the extensions of both the frame and the sliding grip being adapted to be connected by any desired number of rubber bands looped thereover to increase or diminish the resistance of the device to pressure of the operator's grip upon the device.

A further object of the invention is to provide a device of this character which will be formed of a few strong simple and durable parts, which will be inexpensive to manufacture, and which will not easily get out of order.

With the above and other objects in view the invention consists of certain novel details of construction and combinations of parts hereinabove after fully described and claimed, it being understood that various modifications may be resorted to within the scope of the appended claim without departing from the spirit or sacrificing any of the advantages of the invention.

25 In the accompanying drawing, forming part of this specification,

Figure 1 is a front elevation of the grip exerciser constructed in accordance with the invention.

30 Figure 2 is a longitudinal sectional view of the exerciser taken on the line 2—2 of Figure 1.

Figure 3 is a perspective view of the exerciser showing the rubber bands tensioned in full lines and in normal condition in dotted lines.

35 Figure 4 is an end elevation of the exerciser with the rubber bands tensioned.

Referring now to the drawing in which like characters of reference designate similar parts in the various views, 10 designates a substantially rectangular frame formed of stiff wire. A wood or other tube 11 is mounted on one of the transverse members 12 of the frame to provide a stationary grip. The sides of the frame adjacent to the other transverse member 13 are 40 bent outwardly to provide lateral extensions 14 over which a plurality of superposed rubber bands 15 are looped at one end.

A wood or other cylinder 16 is slidably mounted on the sides of the frame to provide a sliding grip. Transverse openings 17 are formed near the ends of the sliding grip to loosely receive the sides of the frame. The ends of the sliding grip project beyond the sides of the frame to provide extensions over which the other ends of the rubber bands are looped.

The sides of the frame are bent outwardly to provide stops 18 which limit movement of the 16 sliding grip away from the stationary grip under urge of the tensioned rubber bands.

In operation the number of rubber bands which connect the extensions of both the frame and the sliding grip may be increased or diminished to adjust the resistance which the device offers to closing of the operator's hand when both the grips 12 and 16 are held in the palm of the hand between the thumb and fingers.

From the above description it is thought that 20 the construction and operation of the invention will be fully understood without further explanation.

What is claimed is:

An exerciser for developing the gripping muscles of the hand comprising a substantially rectangular frame formed of a single length of wire band to provide parallel sides, a transverse member connecting the sides at one end, transverse short members at the other end of the sides 30 forming gudgeons, the sides being directed outwardly adjacent the first named transverse member to provide lateral extensions, the sides being bent outwardly intermediate their ends to provide stops, a roller journaled on said gudgeons 35 and forming a grip, a second roller forming a grip and having an opening slidably receiving said sides adjacent said first named grip, the ends of the second named roller projecting beyond the sides, and rubber bands engaged over 40 said lateral extensions and over the ends of said second named roller adapted to normally hold the ends of the second named roller against said stop.
